UNITED STATES PATENT OFFICE

JAMES G. LYONS, OF STOCKTON, CALIFORNIA

AEROPLANE

Application filed March 6, 1928. Serial No. 259,439.

This invention relates to improvements in aircraft, my principal objects being to provide a machine of this character constructed so that it will have great carrying power with a relatively narrow wing spread; one which can safely alight on water and which can then be properly propelled and navigated while on the water; and one which is provided with power generating devices operated by the 10 air currents set up with the operation of the propellers and the forward movement of the machine.

These objects I accomplish by means of such structure and relative arrangement of 15 parts as will fully appear by a perusal of the following specification and claims.

In the drawings similar characters of reference indicate corresponding parts in the several views:

20 Fig. 1 is a fanciful perspective view showing my improved aeroplane in flight.

Fig. 2 is a top plan view of the machine partly broken out.

Fig. 3 is a front end view, the forward 25 body compartment being shown in section.

Fig. 4 is a longitudinal section of the machine.

Fig. 5 is a longitudinal section of a wing showing a modified air discharge arrangement for the power generating turbines or 30 wind mills.

Fig. 6 is a fragmentary rear end view showing modified form of ground engaging member.

35 Referring now more particularly to the characters of reference on the drawings, and particularly at present to Figs. 1-4, the aeroplane comprises a fuselage or body 1 which is shaped like the hull of a boat and is adapted to float on water on an even keel and to a certain depth just like the hull of a vessel.

The wing structure projects laterally from the upper edge of the hull and comprises a main front end portion 2, which merges unbroken into an intermediate and somewhat narrower portion 3, which portion in turn merges unbroken into the rear portion 4, whose side edges converge to the rear and terminate some distance rearwardly of the 45 rear end of the hull as shown in Fig. 2.

The wing portions 2 toward their outer ends are formed with a downward dip toward the rear as shown at 5 in Fig. 3. This arrangement gives a wing area of the general shaft of that of birds, and with a corresponding effectiveness of lifting and sustaining power; placing the greatest area at the front where it is most needed and gradually decreasing the area toward the rear without any actual break in the supporting 55 surface being had. The main forward propeller 6 is mounted on the nose of the hull and is directly connected to a stationary gas engine 7 or the like which is mounted in the hull at the rear end of the forward compartment 8; the ceiling of which compartment extends to and joins in with the top surface of the wing. The side propellers 9 which are somewhat higher than the central propeller are mounted just under and ahead 60 of the front edge of the wing structure, and are driven from a stationary engine 10 which is mounted in the body below the engine 7, said engine being connected to the propellers by suitable drive connections such as are indicated at 11. Using stationary engines located inside the body makes them very easy 65 to attend and keep in proper working order and they are not exposed to the weather. They may also be positioned where they aid 70 in balancing the machine. The side propellers being higher than the central one they may be operated when the hull is floating on the water to propel the craft without churning up any water.

75 The horizontal direction rudder 12 is located at the rear of the hull and below the rear end wing portion, and extends downwardly to the bottom of the hull. This rudder can therefore be used for steering when 80 the hull is floating on the water as well as when the machine is in flight.

85 The vertical direction rudder 13 projects rearwardly from and is longitudinally aligned with the rear end wing surface and extends 90 alongside the edges of such surface for a certain distance to a junction therewith as shown in Fig. 2. The rudder is pivoted at its forward side tips as indicated at 14. Both 95 rudders are connected to the usual form of con-

trol means indicated at 15 which are mounted in the forward compartment 8 of the body; this being the one occupied by the pilot.

The wing structure is of double hollow construction, with a gradual narrowing toward the rear. Extending lengthwise of the wings between the top and bottom surfaces and adjacent the hull on both sides are air passages 16, which are open to the atmosphere at both ends. These passages communicate intermediate their ends with horizontal casings 17 also inclosed in the wings in which casings air turbine wheels 18 are mounted. These wheels are connected with electric generators 19 or the like which are preferably mounted inside the hull where they may be serviced or inspected whenever necessary. By means of this arrangement a rearward flow of air through the passages 16 set up by the rotation 20 of the propellers and the flight of the machine causes the turbine wheels to be rotated and the generators to be driven, thus generating power for lighting and other purposes. In the type shown in Figs. 1 and 2 the air passages are substantially straight from end to end. In the arrangement shown in Fig. 5 the passage 16^a beyond the turbine casing 17^a has an auxiliary downwardly projecting discharge outlet 20. This enables the air to be 25 discharged downwardly and thereby aids in exerting a lifting power to the adjacent portion of the machine. The flow of air through the outlet 20 or the horizontal termination of the passage 16^a is selectively controlled by a 30 suitable damper 20^a.

The air passages and turbine casings being inclosed in the wings, of themselves, they offer no wind resistance to exert a drag on the forward movement of the plane.

Depending from the lower wing surface to the sides of the propellers 9 are longitudinally extending ridges or deflectors 21. These are positioned relative to the diagonal air currents thrown rearwardly from the central 45 propeller so as to catch such currents and deflect them in a straight rearward direction. This causes the air to be retained and somewhat compressed under the wing structure from front to rear thereof, thereby giving the 50 advantage of the lifting power of such air which would otherwise pass beyond the sides of the wings to no effect. These ridges increase in depth toward the rear so as to substantially equalize the lifting power of these 55 air currents over the length of the wing surfaces with which such air currents are engaged.

The usual landing wheels 22 may be employed if the machine is to be used for land 60 flights and landings on the ground, with the accompanying rear tail skid 23. If desired this skid may be replaced by another wheel 24 as shown in Fig. 6, in which the wheel is shown as being mounted on the lower end of a 65 pivoted arm 25 which is associated with a

yieldable spring member 26. This arrangement enables the wheel to yield rearwardly and upwardly so as to absorb some of the shock of engagement with the ground.

The main cargo or passenger carrying compartment 27 of the body, which is preferably divided off from and is rearwardly of the compartment 8 and the engines, has a floor 28 a sufficient distance from the keel of the hull to provide a space under the floor for fuel tanks 29.

Other fuel tanks 30 are mounted in the forward portions of the wings between the air passages 16 and the outer ends of said wings. The latter tanks may feed to the engines by 80 gravity, since they are above the engines; while the lower tanks must of course have a vacuum or pressure feed means as will be evident.

The ceiling of the main hull compartment 85 may be the top surface of the wings as shown instead of the bottom surface thereof, which bottom surface may be left off where the wings intersect the body. This construction as will be evident gives the advantage of a 90 considerable amount of additional head room over what would otherwise be obtained.

If desired or necessary the upward pressure exerted on the plane by the downward discharge of the air through the passage outlets 20 may be utilized in banking the machine, by merely manipulating the dampers 20^a to open or shut off one or the other of such outlets alternately.

From the foregoing description it will be 100 readily seen that I have produced such a device as substantially fulfills the objects of the invention as set forth herein.

While this specification sets forth in detail the present and preferred construction 105 of the device, still in practice such deviations from such detail may be resorted to as do not form a departure from the spirit of the invention, as defined by the appended claims.

Having thus described my invention what 110 I claim as new and useful and desire to secure by Letters Patent is:

1. An aeroplane including a body and a single wing disposed directly over the body and extending lengthwise thereof to a point beyond the rear end of the same, a vertical rudder mounted entirely under the rear overhanging portion of the wing, and a horizontal rudder hinged in connection with the rear portion of the wing, and projecting rearwardly of the same.

2. An aeroplane including a body, a single hollow wing mounted on the body, and air passages extending lengthwise in the wings to the sides of the body, said passages being open at their front ends to the front edge of the wing, and at their rear ends to the under surface of the wing at different points in the length thereof, and damper means for selec- 130

tively controlling the opening of the rear-end openings of the passages.

3. An aeroplane including a body and a single wing disposed directly over the body and extending for substantially the full length thereof; the side edges of the wing being formed as a plurality of steps to gradually decrease the width of the wing from front to rear in simulation of the outstretched wing area of a bird, in which the foremost and widest step portion of the wing is formed with a downward dip toward its outer ends and in a rearward direction.

In testimony whereof I affix my signature.
